United States Patent Office

Des. 211,748
Patented July 23, 1968

211,748

FORM FILE

Pentti Martti Kalervo Nuora, Tottijarvi, Finland, assignor to Viialan Viila Oy, Viiala, Finland, a company

Filed July 31, 1967, Ser. No. 8,057

Term of patent 14 years

(Cl. D37—1)

FIG. 2

FIG. 1

FIG. 1 is a perspective view of a form file showing my new design; and

FIG. 2 is a sectional view, taken along line 2—2 in FIG. 1, to illustrate alternating concave and planar lateral surfaces of the form file.

I claim:

The ornamental design for a form file, as shown.
